Atkins

UNITED STATES PATENT OFFICE.

CARLOS BENETTI, OF BARCELONA, SPAIN.

CROWN STOPPER.

Application filed May 5, 1925, Serial No. 28,250, and in Spain March 15, 1925.

This invention relates to stoppers for bottles and has for its object to improve the construction of the stoppers so that, although being superior to crown stoppers of known construction, they are of great simplicity, 5 very efficient and economical.

There is no need to emphasize the importance of a good bottle closure.

To obtain a comparatively good and efficient hermetical closing of a bottle by means 10 of a stopper of known type the stopper must not be only good quality cork, but it is further necessary, when gaseous liquids are to be bottled, to insert a disk of impermeable paper between the cork and the metal cap, and 15 to fasten by means of adhesive material the paper on one side to the bottom of the cap and on the other side to the cork. A bottle stopper of this type is considered as giving 20 maximum security for a good closing of the bottle. Notwithstanding the care taken in the manufacture of the above mentioned stopper, it happens frequently that the closure is not perfectly airtight, so that the 25 gases are not retained in the bottle with sufficient security. The reason therefore is that not sufficient pressure is exerted on the stopper, and this pressure cannot be increased on account of the limited resistance of the 30 glass and the material which constitutes the metallic cap. These inconveniences are overcome, according to the present invention, by fitting the metal cap of a bottle stopper with 35 two concentric grooves which may be continuous or each composed of a number of separate sections. The two concentric grooves are in alignment, the outer one with the outer 40 circumference of the bottle neck and the inner one with the inner circumference of the bottle neck. Owing to these concentric grooves in the metal cap no gases can escape 45 from the bottle between the cork and the metal cap. In order to securely hold the metal cap on the cork disk triangular flaps are stamped out of the material of the flange 50 of the metal cap so that they penetrate into the cork disk.

If, for any reasons whatsoever, it should not be desired to make the concentric grooves 55 in the top plate of the metal cap a metal disk may be used which has these concentric grooves and is inserted between the upper surface of the cork disk and the metal cap. The cork disk may further be securely fixed on a metal cover by means of an indentation

pressed into the outer surface of the flange of the metal cover.

Several embodiments of the invention are shown in the accompanying drawings in which:—

Fig. 1 shows in vertical section an improved bottle stopper in closing position on a bottle neck.

Fig. 1^a is top plan view of Fig. 1.

Fig. 2 is a plan view of the metal cap seen 65 from above.

Fig. 2^a is a side elevation of the metal cap and

Fig. 2^b is a plan view seen from below.

Fig. 3 shows in cross section an auxiliary 70 metal disk to be inserted between the cork disk and the metal cap.

Fig. 3^a is a top plan view of Fig. 3.

Fig. 4 shows in section a metal cap with 75 an auxiliary metal disk.

Fig. 4^a is a plan view of Fig. 4.

Fig. 5 shows in plan view from below a cork disk with metal cover.

Fig. 5^a is a section of Fig. 5.

Fig. 5^b is a plan view of Fig. 5^a seen from 80 above.

As shown in Figs. 1, 1^a, 2, 2^a, and 2^b the improved bottle stopper consists of a plain cork disk *a* of slightly greater diameter 85 than the upper end of the bottle neck *b* and of a metal cap *d*. This metal cap *d* has in its top plate two concentric grooves *c*, *c'* and a flange *e*. The concentric grooves *c*, *c'* are preferably continuous as shown in Fig. 2 and arranged so that groove *c'* stands 90 above the inner edge of the bottle neck *b* and groove *c* above the outer edge of the same. These grooves are designed to increase the resistance to tension and exerted 95 on the cork disk at the inner and outer circumference of the bottle neck.

In the flange *e* of the metal cap upwardly directed flaps *f* are arranged which are stamped out of the material of the flange so that they are slightly bent inward.

To close a bottle, a cork disk *a* is placed on the bottle neck whereupon, in the well known manner, a metal cap *d* is placed over said cork disk and clamped under pressure on the bottle neck with the aid of a commonly used machine so that the edge of flange *e* is pressed into the circular groove *g* in the outer surface of the bottle neck. When the metal cap *d* is placed over the cork disk *a* the inwardly projecting flaps *f* 110

2
give way as they are elastic, to penetrate into the cork disk *a* when the same has been strongly compressed by the pressure exerted on and by the metal cap. The cork disk is thus securely fixed in the metal cap. This is necessary as the gases in the closed bottle have the tendency to draw the closure inward so that, as the cork disk is retained in the metal cap, this pressure does not act only upon the cork disk but also upon the metal cap.

Owing to the concentric grooves *c*, *c'* in the top plate of the metal cap gases cannot escape between the cork disk and the metal cap. The gases cannot escape through the openings in the flange *e* produced by the stamping out of the flaps *f* as these openings are tightly closed by the material of the cork disk *a*.

20 The grooves *c*, *c'* might, instead of being continuous, be composed of several separate portions. The flaps *f* in the flange *e* of the metal cap *d* might be of another shape than the triangular shape shown.

25 If, for any reason whatsoever, it should not be desirable to make the concentric grooves in the metal cap *d* an auxiliary metal disk *h* may be used as shown in Figs. 3, 3^a and 4, 4^a. In this auxiliary metal disk *h* the concentric grooves *c*, *c'* are arranged as shown in Figs. 3, 3^a and 4. This auxiliary metal disk *h* is inserted in the

metal cap before the same is placed upon the cork disk.

As shown in Figs. 5, 5^a and 5^b the cork disk *a* may be inserted in a cover *i* of sheet metal and retained in this cover by an indentation *h* in the flange of said sheet metal cover, as shown in Fig. 5^a.

35 The lower surface of the cork disk *a* may have a coating of paraffin or other convenient substance to prevent direct contact between the contents of the bottle and the cork disk so that it is impossible for the taste of the liquid to be impaired by the cork. 40 45

I claim:—

A bottle stopper comprising in combination a plain cork disk of slightly greater diameter than the upper end of the neck of the bottle to be closed, a metal cap having 50 two concentric grooves in its top plate said grooves being in alignment with the outer and inner edges of the bottle neck, respectively and designed to increase the resistance to tension and the pressure exerted on the cork disk at the inner and outer circumference of the bottle neck and inwardly and upwardly directed flaps in the flange of said metal cap said flaps being produced by stamping and designed to securely fix said 55 60 cork disk in said metal cap.

In testimony whereof I have signed my name to this specification.

CARLOS BENETTI.
